BUILDING CONSTRUCTION

Henry E. Sage, West Hartford, Conn.

Application June 7, 1946, Serial No. 675,184

4 Claims. (Cl. 72—1)

1
This invention relates to a building construction and more particularly to a means for securing together different members of a building in such a manner as to retain them firmly united and to provide maximum strength and durability for the entire structure.

An object of this invention is to provide novel means for firmly securing rafters, roof supporting frames, or similar members, in position upon wall upright members and the said upright members vertically upon the building foundation.

A further object of this invention is to provide a construction comprising tubular members secured together by means of strands, such as cables or the like, for reinforcing said members and securing them together.

Further objects and advantages of my invention will be more clearly understood from the following description and from the accompanying drawings, in which:

Fig. 1 is a view in central vertical section, illustrating a building construction embodying my invention.

Fig. 2 is a similar view showing the invention as applied to a modified form of the construction.

Fig. 3 is a view in central vertical section on the line 3—3 of Fig. 2.

The construction shown in the drawings preferably comprises upright tubular posts 5 which are mounted upon a foundation 6 that is formed in the ground, indicated at 7 between form plates 8. A roof frame 9 is supported upon the tops of said posts. This frame is constructed of tubular rafters 10 and a tubular beam 11.

In erecting the frame of a building, the form plates 8 are first placed in the ground to form the foundation 6. Top plates 12 are then placed upon the tops of the plates 8 to support the posts 5—5 which project through the said plates 12 and are supported thereon by means of temporary flanges 13 which are clamped to the posts.

A cable 14 is threaded through the beam 11 and the rafters 10—10 and the ends thereof are permitted to hang downwardly through openings in the beam 11 and lengthwise through the posts 5—5. Weights 15 are then secured to the ends of said cable and permitted to hang between the form plates 8. If desired, the entire unit, consisting of the side posts 5 and the frame 9, may be assembled flat on the ground and then raised vertically and placed with the ends of the posts 5 upon the plates 12.

After the said frame construction is placed in vertical position, the weights 15 will retain it in said position as their weight is applied upon

the flanges 13. If desired, however, suitable temporary bracing members, may be used to securely support the entire frame structure in upright position. In addition, the rafters 10 and the beam 11 may be welded or otherwise suitably fastened at their end portions to provide a more rigid unit.

Cement, or other similar material, may then be poured downwardly through the said posts, from the tops thereof, until the foundation 6 is formed and the posts are filled as shown. This cement is then permitted to harden and thereby embed the ends of the cable 14, together with the weights 15, solidly in the structure.

It will be noted that the cable 14, being threaded through the beam 11 and around through the rafters 10—10, will unite the roof frame so as to firmly secure the rafter against longitudinal displacement upon the beam 11 and thereby reinforce said frame.

In the modified form shown in Fig. 2, the cable is threaded in one direction to the center of the beam 11, then upwardly through the post 16, then downwardly in one of the rafters 10, then through the beam 11 to the opposite end thereof, then upwardly on the other rafter 10, downwardly through the post 16 and outwardly in the other direction through the beam 11 the ends of the cable may hang downwardly through the post 5 in the same manner as in Fig. 1. This construction will firmly secure the rafters 10 to the post 16, as well as to the beam 11, and the entire frame is secured to the uprights 5.

It will be noted that after the required number of the above described units are in position and the cement has been poured, the remainder of the building may be constructed in a conventional manner so that all of the said units will be securely tied together and thereby held in position to render the said building strong and durable.

As shown in Fig. 1, after the building has been erected, the space between the foundation may be filled with cement to form a floor foundation 17 and, if desired, cement blocks 18 may be laid upon the said floor foundation.

The above described construction will provide an economical as well as a very strong and durable building construction.

50 I claim:

1. A building construction comprising a foundation, a pair of tubular upright posts mounted on said foundation, a roof frame mounted on said posts, and a continuous flexible strand extending through said posts and frame and hav-

ing the opposite end portions thereof depending through said posts and secured in said foundation.

2. A building construction comprising a foundation, a pair of upright tubular posts, a tubular frame supported upon said posts, a cable extending through said frame and having portions of the ends thereof depending downwardly through said posts into said foundation, and weights secured to the said ends and embedded in the said foundation for anchoring the construction in position thereon.

3. A building construction comprising a foundation, a pair of upright tubular posts supported upon said foundation, a frame including a tubular beam resting upon the ends of said posts, a pair of tubular rafters inclined upwardly upon said beam, a flexible cable extending through said beam in one direction, through said rafters and then again through said beam in the opposite direction; the ends of said cable extending downwardly through openings in said beam and through said posts, and weights secured to the ends of said cable and embedded in said foundation; the said posts being filled with cement or the like and embedding said cable within said posts.

4. A building construction comprising a foun-

dation, a pair of upright tubular posts supported upon said foundation, a frame including a tubular beam resting upon the ends of said posts, a pair of tubular rafters inclined upwardly upon said beam, a flexible cable extending through said beam in one direction, then through said rafters and again through said beam in the opposite direction, the ends of said cable extending downwardly through openings in said beam and through said posts, and weights secured to the ends of said cable and embedded in said foundation; the said posts being filled with cement or the like and thereby forming an integral body with said foundation and embedding said cable within said posts.
